Application May 26, 1947, Serial No. 139,270
In Great Britain February 21, 1947

Term of patent 14 years

(Cl. D34—5)

To all whom it may concern:

Be it known that I, Charles Bernard Briggs, a British subject, residing at Horbury, in the county of York, England, have invented a new, original, and ornamental Design for a Racquet Press, of which the following is a specification, reference being had to the accompanying drawings, forming part thereof, and wherein:

Fig. 1 is a perspective view of the upper side of a racquet press showing my new design,

Fig. 2 is a perspective view of the underside of the same, and

Fig. 3 is a side elevation thereof.

I claim:

The ornamental design for a racquet press, substantially as shown.

CHARLES BERNARD BRIGGS.
